UNITED STATES PATENT OFFICE.

JOHN TESSEYMAN, OF DAYTON, OHIO.

CAR-AXLE-BOX COVER.

SPECIFICATION forming part of Letters Patent No. 321,664, dated July 7, 1885.

Application filed May 13, 1885. (No model.)

To all whom it may concern:

Be it known that I, JOHN TESSEYMAN, of Dayton, in the county of Montgomery and State of Ohio, have invented new and useful 5 Improvements in Car-Axle-Box Covers; and I do hereby declare that the following is a full, clear, and exact description thereof, reference being had to the accompanying drawings, which form a part of this specification. 10 This invention relates to certain new and novel improvements in the construction of car-axle-box covers.

The invention consists in the peculiar means employed for retaining the cover upon the box 15 against accidental displacement, whether in its open or closed positions, and in the peculiar construction, arrangement, and combinations of the various parts, all as more fully herein-after set forth.

20 Figure 1 is a perspective view showing the cover opened and partly broken away to show the formation of the guiding-grooves in the edges of the cover. Fig. 2 is a side view with the cover closed and partly broken away to 25 show the engagement of the parts. Fig. 3 is a detached perspective of the rear side of the cover. Fig. 4 is a vertical central section with the cover open.

In the accompanying drawings, which form 30 a part of this specification, A represents a car-axle box, and B the door-opening through which the "waste" and lubricant are introduced. At the lower corners of the door-opening and upon the sides of the box are 35 cast the curved wedge-blocks C, the outer or straight edges of which are flush with the edges of the door-opening. At the upper corners are cast the outwardly-projecting lugs D, being a continuation of the bead a at the top 40 of the box. The lugs are rounded upon their tops, while they are flat upon their under sides.

E is the cover, provided upon its two side edges with the inwardly-projecting L-shaped flanges F, and upon the top edge with the 45 curved flange G, uniting at the corners with the flanges F, thus forming a continuous flange upon the two sides and top of the cover, as shown. The flanges F are, near their upper ends, formed upon a curved enlargement from 50 b to c, while from b, which is the point nearest to the inner face of the cover, such flanges

F gradually diverge from the line of the cover to their open ends. Upon the inner face of the cover, and at a point slightly above its center and almost or about in line with the 55 center of the curved enlargement of the side flanges, F, is cast an inwardly-projecting elongated stop, H.

In practice the cover is placed upon the box in such manner that the lugs D will enter the 60 open ends of the flange F. It is then drawn forward until the stop H strikes against the head a upon the upper edge of the box and the lugs D have passed into the enlargement 65 of the side flanges, the position of the cover now being in nearly a horizontal plane. The cover can now be turned upon the lugs D, closely over the door-opening, and, being allowed to drop, the curved wedge-blocks C will enter the side flanges, and by their engagement therewith, and the engagement of the 70 lugs D with the upper portion of said flanges, draw the cover tightly against the edges of the box around the door-opening.

What I claim as my invention is—

75 1. A cover for car-axle boxes provided upon its two side edges with inwardly-projecting flanges, and upon the top edge with a curved flange, uniting at the corners with the side flanges, each of said side flanges formed with 80 a curved enlargement near its upper end, and diverging at the point b from the line of the cover to its open end, substantially as and for the purpose specified.

85 2. In a car-axle box, the combination of the following elements: an axle-box, A, provided at the lower corners of the door-opening with the outwardly-projecting wedge-blocks C, and at the top with a bead, a, terminating at each end in the lugs D, rounded on top and flattened on the bottom, a cover, D, provided with the inwardly-projecting L-shaped flanges F upon its two edges formed upon a curved enlargement near their upper ends, and a curved flange, G, upon the upper edge, when 90 constructed, combined and operating substantially in the manner and for the purposes described.

JOHN TESSEYMAN.
